No. 860,617.

PATENTED JULY 16, 1907.

F. W. WOOD.
NOTE SHEET GUIDE MECHANISM.
APPLICATION FILED AUG. 25, 1908.

UNITED STATES PATENT OFFICE.

FREDERICK W. WOOD, OF KANSAS CITY, MISSOURI, ASSIGNOR TO BERRY-WOOD PIANO PLAYER CO., OF KANSAS CITY, MISSOURI.

NOTE-SHEET-GUIDE MECHANISM.

No. 860,617.

Specification of Letters Patent.

Patented July 16, 1907.

Application filed August 25, 1906. Serial No. 331,968.

To all whom it may concern:

Be it known that I, FREDERICK W. WOOD, a citizen of the United States, residing at Kansas City, in the county of Jackson and State of Missouri, have invented 5 certain new and useful Improvements in Note-Sheet-Guide Mechanisms, of which the following is a specification.

This invention relates to automatic piano playing mechanism and more particularly to that type provided with means to automatically shifting the note sheet laterally in case it tends to creep in the opposite direction and thus result in imperfect tracking with the tracker bar, and my object is to produce mechanism of this character which will operate efficiently 15 and reliably and which is of simple, durable, compact and inexpensive construction.

To this end the invention consists in certain novel and peculiar features of construction and organization of parts as hereinafter described and claimed; and in 20 order that it may be fully understood, reference is to be had to the accompanying drawing, in which—

Figure 1, is a vertical section taken substantially on the line I—I of Fig. 2. Fig. 2, is a top plan view of the same. Fig. 3, is a vertical section of one side of 25 the frame to illustrate the connection between certain parts. Fig. 4, is a vertical section of a portion of the tracker bar. Fig. 5 is a perspective view of a slide forming a part of the tracker bar. Fig. 6, is a side view of a screw for adjusting the slide.

30 In the said drawing, 1 indicates a suitable frame, 2 rolls journaled therein and adapted to be suitably driven and 3, 4, and 5 guide rollers for the note sheet 6, which is adapted to be moved in the direction indicated by the arrow Fig. 1, through the frictional pressure applied thereon by the rolls 2. 7 is the 35 tracker bar carried by the frame and disposed preferably between rollers 4 and 5, for engagement with the note sheet, only a pair of the tracker bar openings 8 being shown and none of the openings of the note 40 sheet, and connected to said openings of the tracker bar are tubes 9 for connection in the usual manner with the player mechanism not shown.

10 and 11 indicate outer and inner openings in the tracker bar and connected to said openings respectively 45 are tubes 12 and 13. The opposite ends of said openings respectively communicate with openings 14 and 15 in the slide 16 arranged to be longitudinally adjusted in the groove 17 in the tracker bar.

18 indicates a groove in the outer end of the slide 50 and 19 a communicating slot.

20 indicates a set screw mounted in the frame 1 and reduced at its end to provide a neck 21 to engage a slot

19 and a head 22 to engage groove 18. By this arrangement it will be seen that when the screw is turned in one direction or the other it will through the swivel relation described impart longitudinal movement to the slide, the object of such movement being to allow for longitudinal expansion or contraction of the note sheet so that the latter when tracking perfectly with the tracker bar shall effectually cover the inner openings 14 and thus prevent air from passing therethrough.

23 indicates a tube extending from tube 12 of the tracker bar to the tube 24 of a valve casing, said last-named tube communicating with the chamber 25 of said casing and through the vent hole 26 with the succession chamber 27 of said casing.

28 is a flexible diaphragm adapted to be normally expanded into chamber 27 by the pressure of air which passes through openings 14 and 10 and tubes 12, 23 and 24.

29 is an opening connecting chamber 27 and 30 of the casing, and 31 an opening connecting chamber 30 with the atmosphere.

32 is a suitably guided valve stem normally held elevated by the expansion of diaphragm 28, and 33, 34 valves, secured to said stem and normally respectively above opening 31 and below casing opening 29, so that air may pass through opening 31 into chamber 30 and thence through tube 35 to a pneumatic 36 equipped with a forked arm 37 pivoted as at 38 to a ring 39, journaled in a groove 40 of a conical roller 41 mounted slidingly on a shaft 42 carried by the arm 43 of the frame.

A second valve casing of substantially the same construction as that described and correspondingly numbered, has its valve stem provided with only a single valve 44 arranged within chamber 30 of the casing and normally held down on and closing opening 29 by atmospheric pressure and the suction exerted in chamber 27, the lower chamber 25 of said valve casing being 90 connected by a tube 45 corresponding to tube 23 to the tube 13, connected to opening 15 which is normally covered by the note sheet as hereinbefore explained, and the chamber 30 of the second valve casing is also connected by tube 35 to a similar pneumatic 36 equipped with a conical roller 41, as hereinbefore explained, 95 and as shown in the drawing. The conical rollers are preferably longitudinally aligned and have their small ends lapping the note sheet, preferably at its underside as shown.

In practice as long as the note sheet is tracking perfectly with the tracker bar the pneumatics are inflated and the conical rollers disposed about as shown clearly in Fig. 2, so as not to interfere with the operation of 100

the mechanism.

the note sheet. If said sheet swerves to the right and therefore exposes opening 15 air enters the latter and passes through the connecting tubes to the chamber 25 of the second valve casing and raises the diaphragm so as to cause the valve to open communication through opening 29 between the suction chamber 27 and chamber 30 and close communication between the latter and the atmosphere through opening 31. As a result the exhaust in the suction chamber effects the instant collapse of the connected pneumatic and therefore causes its forked arm to slide the connected conical roller further under the adjacent edge of the note sheet and impose unusual friction thereon and thus act as a drag for one side of the note sheet so as to compel it to 10 reverse the operation described and move back to its original position, and again cut off the air through opening 15. As this takes place the air in chamber 25 is drawn through the vent hole into the suction chamber 27 and the valve moves downward to its original 15 position and effects the redepression of the diaphragm. Should the note sheet move to the left and cover opening 14, the air to chamber 25 of the first-named valve casing which holds the diaphragm thereof and the valves elevated, is cut off and as a result the air in said chamber 20 is exhausted through the vent hole into the suction chamber and the diaphragm and valves drop, the action of the latter cutting off the passage of air to the connected pneumatic 31 and establishing communication between the suction chamber and the pneumatic 25 to effect the collapse of the latter and the movement of its connected roller further under and in frictional contact with the note sheet so as to act as a drag upon the latter and cause it to move laterally or swerve back to its original position.

30 It will thus be seen that the lateral movement of the note sheet is instrumental through the mechanism described, in returning the note sheet to its original position and compelling it to track perfectly with the tracker bar.

35 From the above description it will be apparent that I have produced a mechanism of the character described possessing the features of advantage enumerated as desirable and that I reserve the right to make all changes in the form, proportion, detail construc-

tion and arrangement of the parts as shall not be a departure from the scope of the appended claims. 45

Having thus described the invention what I claim as new and desire to secure by Letters Patent is:—

1. In a mechanism of the character described, a tracker bar provided with a pair of openings, a note sheet normally covering one of said openings and the other uncovered by said sheet a pair of conical rollers lapping the side margins of the note sheet, and means whereby lateral movement of the note sheet resulting in exposure of the normally covered opening of the tracker bar shall result in moving one of said rollers toward and against the note sheet so as to act as a drag thereon and cause it to reverse such movement and recover said opening. 50

2. In a mechanism of the character described, a tracker bar provided with a pair of openings, a note sheet normally covering one of said openings; a pair of conical rollers lapping the side margins of the note sheet, and means whereby lateral movement of the note sheet resulting in covering the normally exposed opening of the tracker bar shall effect movement of one of said rollers toward and 55 against the note sheet so as to act as a drag on the latter and cause it to reverse such lateral movement and again uncover said opening. 60

3. In a mechanism of the character described, a tracker bar provided with a pair of openings, a note sheet normally covering one of said openings, a pair of conical rollers lapping the side margins of the note sheet, means whereby lateral movement of the note sheet resulting in exposure of the normally covered opening of the tracker bar shall result in moving one of said rollers toward and 70 against the note sheet so as to act as a drag thereon and cause it to reverse such movement and recover said opening, and means whereby lateral movement of the note sheet which results in covering the normally exposed opening of the tracker bar shall effect movement of the other roller 75 toward and against the note sheet so as to act as a drag on the latter and cause it to reverse such lateral movement and again uncover said opening. 80

4. In a mechanism of the character described, a tracker bar provided with a pair of openings, a pair of conical rollers contiguous to and having their longitudinal axes substantially parallel with said tracker bar, means for automatically moving either of said rollers longitudinally, and means for automatically returning said roller to its original position. 85

In testimony whereof I affix my signature, in the presence of two witnesses.
